UNITED STATES PATENT OFFICE.

EDWARD G. SCHENK, OF LOUISVILLE, KENTUCKY.

WINDOW-SCREEN.

1,143,863.

Specification of Letters Patent. Patented June 22, 1915.

Application filed September 1, 1914. Serial No. 859,636.

To all whom it may concern:

Be it known that I, EDWARD G. SCHENK, a citizen of the United States, residing at Louisville, in the county of Jefferson and State of Kentucky, have invented certain new and useful Improvements in Window-Screens, of which the following is a specification.

This invention relates to window screens which are carried by a spring roller; and the invention has for its object to provide a simple and cheap screen of this kind, together with novel and improved means for guiding the same and holding it against being disarranged.

In order that the invention may be better understood, reference is had to the accompanying drawing, in which—

Figure 1 is an elevation of the screen, with parts broken away and in section; Fig. 2 is a horizontal section on the line 2—2 of Fig. 1, Fig. 3 is a cross section on the line 3—3 of Fig. 2, and Fig. 4 is a vertical section of a modification showing a combined shade and screen.

Referring specifically to the drawing, 5 denotes the jambs of a window frame. The screen is shown at 6, the same being carried by an ordinary spring roller 7 mounted at the head of the window frame. To the lower end of the screen 6 is secured a rigid rod 8 which extends entirely across the screen and carries anti-friction rollers 9 at its ends, said rollers working in guide channels 10 mounted in the inner edges of the jambs 5.

In order to prevent the wind from disarranging the screen 6, strips of cloth are stitched or otherwise secured to one side of the screen at several points, in such a manner as to form pockets 11 to receive rigid cross bars 12 of wood or metal, said cross bars being long enough to project at their ends into the channels 10. The cross bars 12 impart sufficient rigidity to the screen to

permit the use of ordinary mosquito netting or similar cheap screen fabric, in view of which the screen can be easily and cheaply made. This material also allows the screen to be readily wound on the spring roller 7. 50 The cross bars are removable from the pockets in order that the screen may be taken down and washed.

In another form, this invention appears in a flexible screen 13 attached to the bottom 55 of an ordinary spring-wound window shade 14, running in the channels 10 on the window jambs, the flexible screen folding itself at the bottom of window when shade is pulled down. At the bottom of the shade is a rigid cross bar 15 extending at its ends into the channels, to which cross bar the screen is attached.

I claim:

1. The combination with the jambs of a 65 window frame the inner edges of which have guide channels; of a rolling screen composed of a flexible fabric having transverse pockets, and rigid cross bars removably mounted in said pockets and projecting at their ends 70 into the aforesaid guide channels.

2. The combination of the jambs of a window frame, with a shade wound up on a spring roller, and having a rigid cross bar 75 at the bottom, channels in said window jambs for guiding said shade and cross bar, a flexible screen attached to said cross bar, and having its edge extending into said channels on either side, and pockets in said screen at intervals for holding additional 80 cross bars running in said channels to hold the said screen in position in said channels of said window jambs.

In testimony whereof I affix my signature in presence of two witnesses.

EDWARD G. SCHENK.
